UNITED STATES PATENT OFFICE.

GEORGE H. PERKINS, OF PHILADELPHIA, PENNSYLVANIA.

ELECTRIC LIGHTING APPARATUS.

SPECIFICATION forming part of Letters Patent No. 245,393, dated August 9, 1881.

Application filed April 20, 1881. (No model.)

To all whom it may concern:

Be it known that I, GEORGE H. PERKINS, of Philadelphia, Pennsylvania, have invented an Improvement in Electric Lighting Apparatus, of which the following is a specification.

5 My invention relates to electric lighting apparatus in general; and its object is the provision of a transparent casing or outer envelope, by the employment of which, in connection with any known form of electric light, such light is rendered safe for use in explosive atmospheres of the character existing in oil-refineries, flouring-mills, elevators, and the holds of vessels carrying petroleum or its products, 10 and in other atmospheres where danger might otherwise attend its use. To the above end my invention consists in the apparatus hereinafter set forth and claimed.

15 In the accompanying drawings, Figure 1 represents, in perspective, an apparatus conveniently embodying my invention. Fig. 2 is a vertical central section of the same. Fig. 3 is a partial vertical central section of the upper portion of the same, taken in a plane at right angles to the plane through which the section of Fig. 2 is taken. Fig. 4 is a sectional plan view taken on the line *a a* of Fig. 2 and viewed from above. Fig. 5 is a partial central section of the lower portion of the cylindrical 20 stack, taken in the plane of Fig. 3, and exhibiting the arrangement of the lower extremities of one of the guideways of the lower cross-head and the connection of the stop-bar thereto. Fig. 6 is a side sectional magnified detail 25 of the connection of the inclosing-cage with the stack; and Fig. 7 is a view, in perspective detail, of the method of wrapping or covering the strands of the cage-supporting basket.

30 Similar letters of reference indicate corresponding parts wherever used.

35 In the accompanying drawings, A represents the roof of a building in which the vapors from petroleum or other explosive vapors exist to such an extent that the introduction of a naked light would either produce or occasion risk of an explosion, and from which it is desired to suspend an electric light.

40 B is a stack, being a cylinder of metal of suitable proportions secured by means of a circular angle-iron, E, to the roof through an orifice therein, and properly braced or stayed

thereto. The stack is above the roof, surrounded by a cap, C, removably secured by cap-prongs D, which retain the cap, when in place, in such relation to the stack as to be 55 slightly elevated above its upper edge, so as to exclude rain and snow.

Around the lower extremity of the stack is fitted a band, F, the lower edge of which is turned in at a right angle to form a flange, G, 60 and is provided with a circular washer, H, of india-rubber or kindred material, stitched, riveted, cemented, or otherwise secured thereto. The band F is secured to the stack by means of hasps I or other connecting devices. 65

J is a cage, of glass or its equivalent, formed as a cylinder, open on top but closed below, the lower closed portion being, preferably, of hemispherical contour. The diameter of the cage is slightly less than the diameter of the 70 circular opening in the flange of the band F, while it is greater than that of the rubber washer, the result of such proportional relationship being that when the cage is entered from above and moved downward through the 75 stack it passes through the rubber washer and turns it down at an angle, so that the washer presses against the side of the cage, makes an air-tight joint between the cage and the washer, and aids to retain the cage in frictional contact with the washer. In the application of the band to the stack the lower edge of the stack comes in contact with that portion of the rubber washer which is secured to the flange of the band, and when the hasps I are fastened embeds itself therein so as to form an air-tight joint between the band and the stack. 80 When the cage is entered within the washer from below the washer is turned upward instead of downward. 85

90 K is a basket to support the cage, formed of the fewest possible number of strands of wire, wrapped with felting or other fit material, as shown in Fig. 7, or formed of rope or the like. The brim-piece of the basket is connected by 95 means of chains or other connecting devices K' to brackets L, laterally projected from the band, whereby the cage, through the medium of the chains and the basket, is connected with and supported from the band. In lieu of the basket, however, it is obvious that an outwardly-extending bead may be cast around the upper 100

edge of the cage, which, resting upon the washer above the flange of the band, will support the cage.

M is the base-plate of the light, from which 5 is suitably erected the lower carbon point, N, while vertical standards O O connect it with the lower cross-head, P, from which depends the regulating device Q, which places and retains the upper carbon, R, in proper relative 10 position to the lower carbon, N, in the manner common to lights of the character represented. S and T are the positive and negative wires of the carbons, which act also as suspenders to connect the lower cross-head with the upper 15 cross-head, U.

V W are guideways, of any fit construction, formed within or connected to the interior of the stack in the line of the length thereof. These guideways serve to guide in introduction 20 and steady in position the lower cross-head in the introduction of the lighting apparatus proper within the stack.

X are stop-bars, adjustably connected with the guideways by pinning devices Y or the like, 25 which serve to limit the depth to which the lower cross-head can be introduced within the stack, while the upper cross-head rests upon the upper edge of the stack.

Such being the construction of a convenient 30 embodiment of my invention, I desire to state that I do not limit myself to the exact structure and arrangement of detailed mechanical devices hereinbefore represented and described, as I contemplate resorting to many allied or 35 equivalent constructions of minor devices which contribute to complete the embodiment of my invention.

It will, I think, be apparent that lights other 40 than electric lights can be burned with entire safety in explosive atmospheres by their employment in connection with my invention.

It is obvious that there is no means by which 45 the atmosphere within the building can gain access to the light, while the only communication with any atmosphere afforded the light is with the outside atmosphere or that without the building.

When desired, the stack can be prolonged to any extent required to conduct it outside of a building, so as to enable the employment of my 50 invention in connection with lights placed beneath ceilings or floors not in immediate proximity to the outer atmosphere. In the application also of my invention to the loading of vessels with petroleum or its products the apparatus is provided with a stack or tube of such a length that, when the device is lowered through the hatchway until the light assumes its proper position in the hold, the top of the stack or tube will project above the upper deck. 55 60

It will, finally, be understood that the purposes of my invention would be subserved by extending the cage upward to form a stack and providing other means of suspending the lighting apparatus, it being the essence of the 65 invention that the light should be excluded from inside atmospheres and have communication only with the outside air.

Having thus described my invention, I claim—

1. The combination of the stack, band, washer, and cage, substantially in the manner and for the purposes set forth.

2. The combination of the stack, band, washer, cage, and basket, in the manner and 75 for the purposes set forth.

3. As a means of supporting the cage in proper relation to the band and washer, the basket suitably connected to and depending from the band.

4. In combination with the stack, guideways provided with stop-bars, adjustably connected thereto and adapted to sustain the lighting apparatus in proper position relatively to the stack and cage.

In testimony whereof I have hereunto signed my name this 9th day of April, A. D. 1881.

GEORGE H. PERKINS.

In presence of—

C. BERKELEY TAYLOR,
J. BONSALL TAYLOR.
